(57) **CLAIM**

The ornamental design for a digital camera display screen with transitional graphical user interface, as shown and described.

DESCRIPTION

FIG. 1 is a perspective view of a first embodiment of the first image in a sequence for a digital camera display screen with transitional graphical user interface, viewed from the rear side thereof, showing our new design; FIG. 2 is a front view thereof.

FIG. 3 is a rear view thereof.

FIG. 4 is a top view thereof.

FIG. 5 is a left side view thereof.

FIG. 6 is an enlarged view thereof, showing the display screen separately for clarity of illustration;

FIG. 7 is a second image thereof; and

FIG. 8 is a perspective view showing the design of FIG. 1 in the context of different environment.

FIG. 9 is a perspective view of a second embodiment of the first image in a sequence for a digital camera display screen with transitional graphical user interface, viewed from the rear side thereof, showing our new design; FIG. 10 is a front view thereof.

FIG. 11 is a rear view thereof.

FIG. 12 is a top view thereof.

FIG. 13 is a left side view thereof.

FIG. 14 is an enlarged view thereof, showing the display screen separately for clarity of illustration;

FIG. 15 is a second image thereof; and,

FIG. 16 is a perspective view showing the design of FIG. 9 in the context of different environment.

(Continued)

The appearance of the transitional image sequentially transitions between the images shown in FIGS. 6-7 and FIGS. 14-15. The process or period in which one image transitions to another image forms no part of the claimed design. The broken line showing of the digital camera and remainder of display show the environment and form no part of the claimed design.
